UNITED STATES PATENT OFFICE.

AUGUSTUS F. DONALDSON, OF TOLEDO, OHIO, ASSIGNOR TO THE BUNTING BRASS & BRONZE COMPANY, OF TOLEDO, OHIO, A CORPORATION OF OHIO.

BROACHING-MACHINE.

1,318,485.

Specification of Letters Patent. Patented Oct. 14, 1919.

Application filed May 19, 1917. Serial No. 169,643.

To all whom it may concern:

Be it known that I, AUGUSTUS F. DONALDSON, a citizen of the United States, and a resident of Toledo, in the county of Lucas 5 and State of Ohio, have invented a certain new and useful Broaching-Machine; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 My invention relates to broaching machines and it has for its object to provide an efficient broaching machine that will rapidly broach articles. The extremely great pressure required to broach articles by a rapidly 20 moving ram makes it exceedingly difficult to produce a commercially operative automatic feed control machine which will turn out bushings or other articles with a smooth correct bore.

25 I have also provided a centering means which will automatically center the bushings or other articles and will readily coact with the feeding means in receiving the articles and coact with the feeding means 30 in the ejection of the articles.

The invention may be contained in construction of different forms. I have selected one of such construction as an example of constructions containing the invention and 35 shall describe it hereinafter. The construction selected is illustrated in the drawings.

Figure 1 of the drawings illustrates a side view of part of the machine. Fig. 2 illustrates a broken view of the feed operating 40 mechanism. Fig. 3 illustrates a sectional view of a part of the centering means taken on line 3-3 indicated in Fig. 4. Fig. 4 is a top view of the bed plate of the machine. Fig. 5 is a top view of the bed plate above 45 the stripper plate. Fig. 6 is a sectional view taken on line 6-6 indicated in Fig. 5.

1, Fig. 1, is a ram. 2 is a broach. 3 is a bed plate. A suitable means is provided for moving the broach relative to the bed plate, 50 such as crank and connecting rod.

Articles such as bushings are fed beneath the broach in the broaching operation. They are guided to the automatic feeding means by the guides formed of angle irons 55 4, and a rod 44 secured to a bracket 45. The

bushings 5 are engaged one by one by the end of the feed rod 6 which is moved intermittently by the ram 1.

The rod 6 is connected by an arm 7 to a rod 8 which passes beneath the top surface 60 of the bed plate and to a bracket 9 secured to a suitable part of the machine. A rod 10 is secured to the rod 8. A compression spring 11 is placed around the rod 10 and between a washer 12 and the bracket 9 to 65 cause return of the rod to normal or bushing centering position. A lever arm 13 engages the end of the rod 8 to move it to bushing engaging position. The lever 13 may be pivoted to the bed plate 3. It is 70 provided with a roller 14 which is operated upon by the rod 15 that is connected to the ram 1 by a suitable means such as the arm 16. The rod 15 is beveled at its end 40 so as to engage the roller 14 and 75 push the lever 13 toward the plate which coacts with the spring 11 to move the feed rod 6 back and forth. The length of the rod 15 is such that the feed rod 6 is moved inward by the spring 11 when the ram has 80 drawn the broach away from the bed plate and from the bushings.

A stripper plate 16 of hardened metal is located above the bushings. It is securely held in position by a plate 17 in which it is 85 socketed and which is bolted to the bed plate 3. The stripper plate 16 strips the bushings from the broach as it is withdrawn after broaching.

The centering means is located beneath 90 the stripper plate 16. A hardened plate 18 having a surface located at a slight angle to the direction of movement of the feed rod 6 is bolted to an adjustable plate or member 19 which is located in a slotted way 20 located in a plate 22 which is secured to the bed 3. Opposite the plate 18 is disposed a coacting yielding centering member 23 having ears 24. Within the ears there are located a pair of rollers 25 that engage the 95 bushings and push them against the plate 18 by the action of the spring 26. The sliding member 23 moves between angle irons 27 and is pushed forward by the spring 26 which is located between the rod or plate 29 100 and the member 23. The forward movement is limited by the stops 30, 31 located on the member 23 and the plate 32 which is adjustably bolted on one of the angle irons 27. It may be locked from movement 105 110

and away from the work when desired, by the screw 33, which passes through the slot 34 formed in the member 23.

The stops 31 and 30 permit the rollers 25 to be so placed relative to the plate 18 that it requires a little push by the rod 6 to move the bushings between the first roller 25 and the plate 18, but when it passes the roller it is carried by the roller and its pressure 10 thereon against the other roller so that the bushing is held by the pressure of the spring 26 between the rollers and the plate or anvil 18 and in alinement with the broach 2.

The broach, in the operation, moves 15 downward, the feed rod 6 being drawn back in position to engage a bushing. The broach passes through the bushing in centered position, the rod 6 being held back by the rod 15, and through the opening 35 in the bed 20 plate 3 and then returns, the bushing being engaged by the stripper plate and removed from the broach. The rod 6 then is permitted to move forward by the action of the spring 11 pushing a bushing into position of 25 engagement by the roller 25 which centers the bushing for the next operation.

The bushings are directed away from the broach by the angle irons 43.

I claim:

30 1. In a broaching machine the combination of a ram, a broach secured to the ram, a feeding means, a centering means for centering the articles operated upon by the broach to which they are fed by the feeding 35 means, and coöperating with the feeding means for ejecting the articles from beneath the broach.

2. In a broaching machine the combination of a ram, a broach connected to the ram, 40 a feed rod operated by the ram, a yielding centering means having a plurality of rotatable centering members for centering the articles operated upon by the broach.

3. In a broaching machine the combination of a ram, a broach connected to the ram, a feed member, means for operating the member, a yielding centering means having a plurality of rotatable centering members for centering the articles operated upon by the broach, and coöperating with the feed member for ejecting the articles from beneath the broach.

4. In a broaching machine the combination of a ram, a broach connected to the ram,

a feed rod operated by the ram, a yielding 55 centering means having a plurality of rotatable centering members for centering the articles operated upon by the broach, and coöperating with the feed rod for ejecting the articles from beneath the broach, and guides for guiding the articles to the end of the feed rod and to the rotatable members and away from the rotatable members.

5. In a machine for broaching cylindrical articles, a ram, a broach connected to the 60 ram, an anvil, and a pair of rotatable cylindrical coating centering members for pressing the cylindrical articles at two points against the anvil.

6. In a machine for broaching cylindrical 70 bodies, a ram, a broach connected to the ram, a feeding means, a pair of rotatable cylindrical centering members for engaging and centering the articles operated upon by the broach.

7. In a broaching machine, a ram, a broach connected to the ram, a yielding centering means having a plurality of rotatable centering members for centering the articles operated upon by the broach, a member for 80 forcing the articles to a point to be engaged by the rotatable centering members.

8. In a broaching machine, a ram, a broach connected to the ram, a feed member, means for operating the member, a plurality 85 of cylindrical centering members for centering the articles operated upon by the broach and coöperating with the feed member to eject the articles from beneath the broach, a stripper plate for removing articles from the broach.

9. In a broaching machine, a ram, a broach secured to the ram, a feed member, a centering means for centering the articles operated upon by the broach to which they 95 are fed by the feeding member, the centering means having an anvil and a pair of yielding rollers, the rollers for pressing the articles at two points and against the anvil.

10. In a machine for broaching bushings, 100 a ram, a broach connected to the ram, a feeding means and a centering means having an anvil and a pair of yieldable contact members for forcing the bushing against the anvil for centering it beneath the broach. 105

In testimony whereof, I have hereunto signed my name to this specification.

AUGUSTUS F. DONALDSON.
